UNITED STATES PATENT OFFICE

JOE J. ETTINGER, OF WARSAW, INDIANA, ASSIGNOR TO ZIMMER MANUFACTURING COMPANY, OF WARSAW, INDIANA, A CORPORATION

SURGICAL SPLINT

Application filed December 5, 1927. Serial No. 237,622.

The invention relates to surgical splints and it is particularly directed to splints adapted for use in connection with a fractured metacarpal bone.

5 The object of the invention is to provide a metacarpal splint that will fit the contour of the anterior surface of the hand and fingers in the usual or normal position in which the hand is held and thereby contribute materially to the ease and comfort of the patient and afford uniform pressure at all points of bearing.

An embodiment of the invention is illustrated in the accompanying drawings, in which

15 Figure 1 is a plan view of the splint; Fig. 2 a rear elevational view of the same; Fig. 3 a side view of the splint and Fig. 4 an elevational view of the splint taken at the opposite side thereof.

20 Referring to the illustrative embodiment of the invention the body 1 of the splint is preferably cast of aluminum or other light metal, the interior being hollow or cored. The openings 2 and 3 at the opposite sides of the splint permit the gauze or tape 4 to be passed through the splint for the purpose of binding the hand onto the splint.

25 The forward portion or finger supporting section 5 of the body of the splint is relatively thick and the rear or palm supporting section tapers in a vertical plane. In order that the top side of the body shall fit the contour of the anterior surface of the hand the top side 30 of the section 5 and the forward end of the body are convex both transversely and longitudinally, one side of section 5 being extended laterally at 6 and rounded to form a concave receiving space 7 for the first finger 35 of the hand, the first two phalanges of the thumb being engaged under said extension 6. At the opposite side of the body 1 the section 5 is concaved to form a receiving space 8 for the little finger of the hand. The convex 40 surface between the annular space 7 and the space 8 is adapted to receive the second and third fingers and the adjacent portion of the palm. The fingers extend about the forward 45 end of the body in the natural manner in which the fingers are normally carried.

The section 9 of the top surface of the body 1, rearwardly of the section 5, is the palmar section. A transversely rounded ridge 10 extends in a diagonal direction on the section 9 from the section 5 toward the rear end of the body, and upon opposite sides of the ridge the section slopes downwardly transversely and longitudinally to form a surface 11 to receive the fleshy part of the thumb and a surface 12 to receive the fleshy part of the palm along the outer side of the hand, the ridge 10 being engaged by the palm between the thumb and said outer fleshy part of the palm.

55 The rear edge of the splint is preferably curved and is inclined upwardly from the thumb supporting side toward the opposite side.

60 The rear portion 13 of the bottom of the splint curves upwardly and presents a twisted effect.

65 The various surfaces of the top of the splint above described, when the hand is taped or bound to the splint, cause the splint to fit the palm of the hand and the under 70 surfaces of the fingers and thumb in the natural position of the hand, thereby affording comfort and ease to the patient and uniform pressure at all points of bearing of the hand upon the splint.

75 It is to be noted that the drawings illustrate a splint adapted for use on the right hand. The splint for the left hand will be similar to the splint illustrated except that the various surfaces will be reversed to accommodate the left hand.

80 What I claim is:

1. A splint consisting of a body having a finger supporting section on its surface at and adjacent one end and having a palm supporting section between said finger supporting section and the rear end of the body, a lateral projection on the body adapted to be received between the first finger and the thumb, the finger-supporting section being convex and the palm-supporting section having depressions at its opposite sides adapted to be engaged by the fleshy portions of said palm and the bottom of the body being convex longitudinally.

2. A metacarpal splint consisting of a hollow body having its top surface and forward end convex for engagement by the fingers of the hand, and having its rear portion tapering in a vertical plane, the top surface of said rear portion having depressions upon opposite sides to receive the fleshy portions of the palm of the hand, an annular projection on one side of the body adapted to be engaged on its upper and forward side surfaces by the first finger of a hand and upon its rear and lower surfaces by the thumb, the body having aligned apertures in its opposite sides to receive a member adapted to bind the hand upon the said body.
3. A metacarpal splint comprising a hollow body, an apertured substantially cylindrical hollow boss on one side of the body, the opposite side of the body having an aperture therein, said apertures being adapted to permit the lacing of a band through the body for binding the human hand upon the body, the top surface of the body between the apertured walls being convex in the central portion thereof and concave adjacent each of said apertured walls, the forward end wall being convex longitudinally and transversely, and the section of the top surface rearwardly of the said convex surface thereof being concaved longitudinally and transversely toward the edge of the body to form palm engaging surfaces for the hand.

In witness whereof I have hereunto signed my name this 19th day of November, 1927.

JOE J. ETTINGER.
